UNITED STATES PATENT OFFICE.

MEYER GREITZER, OF NEW YORK, N. Y.

LAMP SHADE.

1,423,319.

Specification of Letters Patent.

Patented July 18, 1922.

Application filed August 31, 1921. Serial No. 497,082.

To all whom it may concern:

Be it known that I, MEYER GREITZER, a citizen of Russia, residing at 1063 Fox Street, city of New York, county of Bronx, State of New York, have invented new and useful Improvements in Lamp Shades, of which the following is a specification.

This invention relates to improvements in lamp shades, and more especially to shades for drop lights, the principal object of the invention being to provide a shade for a light of this character whereby the light can be directed on a comparatively small area in any desired direction.

With the foregoing and other objects in view, which will appear as the description proceeds, the invention consists in the novel features of construction and combination of parts which will be more fully described hereinafter, and particularly pointed out in the claims.

In the drawings accompanying and forming part of this specification:

Fig. 1 is a side elevation, partly broken away, of an electric drop light provided with a shade constructed in accordance with the present invention; and

Fig. 2 is a partly sectional side elevation taken at right angles to Fig. 1, the light directing member being shown in full lines in one extreme position and in dotted lines in the other extreme position.

The same characters of reference designate the same parts in the different figures of the drawings.

Referring to the drawings, 2 designates a shade holder of the usual construction attached to a drop light socket 3 carrying a light bulb 4, the holder being provided with the usual thumb screws 5 for retaining the shade.

The shade forming the subject matter of the present invention comprises a spherical member 6 having an opening provided with a suitably curved edge for attachment to the holder in the usual manner. The shade is further provided with an elongated slot 7 extending preferably from a point diametrically opposite the shade holder to within a short distance from the holder-connecting edge of the shade, and within this slot is secured for reciprocation from one end of the slot to the other a flared tubular light-directing member 8, the end walls of the slot being curved to fit the outer side of said member. Secured to the member 8,

within the shade, is a slot-closing member or follower 9, having a curvature corresponding to that of the shade and provided with an opening of sufficient diameter to fit snugly over the inner end of the member 8, said member being upset or flanged as shown at 10 thereby to securely retain the slot closing member 9 thereon. It will thus be seen that when the directing member 8 is moved from one end of the slot to the other, as for instance from the position shown in full lines to the dotted line position illustrated in Fig. 2, the follower 9 will move with it and thus close the slot after the member 8 has passed. A second slot closing member or follower is provided within the shade at the side of the directing member 8 opposite from the follower 9. This second follower, however, is made up of a plurality of telescoping members 11, each slidable within the next succeeding member and having its longitudinal edges turned over those of said succeeding member thereby to prevent lateral disengagement of said members. In order to prevent the members 11 from sliding out of engagement with each other, they are provided adjacent their ends with an indentation 12, whereby when the members are extended into slot-closing position, any tendency to pull apart will be resisted by the engagement of the indentation at the rear end of one with that at the front end of the next succeeding member, as clearly shown in Fig. 2. The foremost member 11 is similarly connected to the end of the member 9 and the rearmost member 11 to a fixed member 13 secured within and above the upper end of the slot 7. If desired, the shade may be provided with an outwardly pressed depression 14 for guiding the followers in their travel.

In operation, when the member 8 is in the position shown in full lines in Fig. 2, the light will be directed on an area directly below the bulb, while the portion of the slot not occupied by the light-directing member will be covered by the telescoping members 11, thereby preventing escape of light through said slot. When, however, it is desired to direct the light on an area at an angle thereto, the member 8 is moved along the slot 7 to the proper point, the movement of the member 8 causing the members 11 to telescope one within the other, while the member 9 follows the light-directing mem-

ber 8 and covers the slot, and in its turn prevents escape of light. When the light-directing member is in the upper extreme position shown in dotted lines in Fig. 2, the telescoping members 11, together with the portion of the member 9 shown at the left of the light-directing member in Fig. 2 will be nested within the fixed member 13.

From the foregoing it will be seen that I have provided a shade by means of which the light can be directed on any desired area at any angle below the upper end of the slot, and anywhere around the circumference of the lamp, since if it is desired to direct the light, for instance, toward an area in the same horizontal plane but at right angles to the dotted position of the member 8 in Fig. 2, it would only be necessary to release the thumb screws 5 and rotate the shade to the proper position.

It is to be understood that while I have described in detail the structure herein illustrated, I do not thereby limit my invention to the precise features of construction shown, as I am aware that many mechanical changes and modifications may be made therein without departing from the spirit and scope of the claims appended hereto.

Having thus described my invention, what I claim is:

1. A lamp shade, comprising a spherical member adapted to be removably secured to a lamp and provided with an elongated opening, a light-directing member movable within said opening, and means for closing the portions of the opening not occupied by said movable member.
2. A lamp shade, comprising a spherical member adapted to be removably secured to a lamp and provided with an elongated opening, a light-directing member movable within said opening, and means movable with said last member for closing the por-

tions of the opening not occupied by said movable member.

45

3. A lamp shade, comprising a spherical member adapted to be removably secured to a lamp and provided with an elongated opening, a tubular member movable within said opening for directing the light at different angles, and means secured to said tubular member and movable therewith for closing the portions of the openings not occupied by said movable member.

50

4. A lamp shade, comprising a globe adapted to be removably secured to a lamp and provided with an elongated slot, a light-directing member movable from one end of said slot to the other, and slot-closing members at opposite sides of said light-directing member for closing the portions of said slot not occupied by the light-directing member.

55

5. A lamp shade, comprising a globe adapted to be removably secured to a lamp and provided with an elongated slot, a light-directing member movable from one end of said slot to the other, and slot-closing members at opposite sides of said light-directing member for closing the portions of said slot not occupied by the light-directing member, one of said slot-closing members comprising a plurality of telescopic members.

60

6. A lamp shade, comprising a globe adapted to be removably secured to a lamp and provided with an elongated slot, a light-directing member movable from one end of said slot to the other, and slot-closing members at opposite sides of said light-directing member and movable therewith for closing the portions of said slot not occupied by the light-directing member, one of said slot-closing members comprising a plurality of telescopic members.

65

In testimony whereof I have signed my name to this specification.

MEYER GREITZER.
